United States Patent Office

Des. 196,370
Patented Sept. 24, 1963

196,370

TABLE

Forest Wilson, P.O. Box 6, Medinah, Ill.

Filed Aug. 1, 1961, Ser. No. 66,151

Term of patent 14 years

(Cl. D33—14)

FIG. 1

FIG. 3

FIG. 2

FIG. 1 is a perspective view of a table according to the present invention;

FIG. 2 is a front elevational view of the table on a reduced scale; and

FIG. 3 is a top plan view thereof.

The essential features of the design reside in the portions shown in full lines on the drawings.

I claim:

The ornamental design for a table, substantially as shown and described.
